UNITED STATES PATENT OFFICE.

WEBER J. FOX, OF SAN DIEGO, CALIFORNIA.

SELF-SERVING TABLE AND HEATER.

1,158,475.

Specification of Letters Patent.

Patented Nov. 2, 1915.

Application filed February 19, 1915. Serial No. 9,362.

To all whom it may concern:

Be it known that I, WEBER J. FOX, a citizen of the United States, residing at San Diego, in the county of San Diego and State of California, have invented new and useful Improvements in Self-Serving Tables and Heaters, of which the following is a specification.

This invention relates to improvements in tables and has particular reference to that class of devices known as self-serving tables.

The invention has for its object the provision of a device of this character including a rotary top whereby the vessels containing the food can be brought into convenient reach of anyone at the table, and embodying a novel construction of means to retain heat in certain edibles, desired to be kept hot after the different vessels containing them are placed upon the table.

Other objects will appear as the nature of the invention is better understood from the following description, the invention residing in the specific construction, combination and arrangement of parts hereinafter more fully described.

In the drawing forming a part of this application like numerals of reference indicate similar parts in the several views and in which:

Figure 1 is a top plan view. Fig. 2 is a bottom plan view. Fig. 3 is a longitudinal sectional view. Fig. 4 is a top plan view with the inner section of the table removed. Fig. 5 is a detail perspective view of the pedestal. Fig. 6 is an enlarged vertical sectional view.

As shown in one embodiment of the invention, the same essentially consists of a pedestal 5 having the usual feet 6. The upper end of the pedestal is provided with diametrically disposed recesses 7 for the reception of the cross bars 8, the latter being secured in position by means of the bolts 9 as shown.

The top of the table comprises what may be termed an outer section 10 fixed in any suitable manner upon the bars 8 adjacent the ends thereof. The upper edges of the bars 8 are rabbeted as at 11 from a point adjacent the inner periphery of the stationary section 10, so that when the inner rotatable section 12 is in position it will lie flush with the outer section 10. Depending centrally from the section 12 is a sleeve 13 received by an opening 14 in the bars 8 at their point

of intersection, whereby the section 12 is mounted for rotation within the outer section 10, the sleeve 13 being held in position relatively to the cross bars 8 by means of the nut 13'. The opening 14 has arranged therein a collar 15 in which are fitted the anti-frictional ball bearings 16. Each of the bars 8 at equidistant points from their point of intersection is provided with a recess 17 in which is journaled the rollers 18, the latter lying slightly above the upper surface of the bars upon which the inner section is supported for rotation. At diametrically opposite points, the inner section 12 is provided with small knobs 19 adapted to be grasped to rotate the same, whereby the various vessels containing the food, and supported thereon can be brought into convenient reach of anyone at the table. The knobs of course can be secured to the section 12 in any suitable manner, but however it is preferred to have the knobs formed with a threaded shank 20 to screw into sockets formed in the section, whereby the knobs can be removed when desired.

With a view of retaining the heat in certain foods desired to be kept hot after being placed upon the table, I make use of a number of disks 21 adapted to be arranged upon the top of the inner section 12 as shown, and capable of being shifted to any desired position thereon. It might here be stated that any number of these disks may be employed as found necessary, in consideration with the size of the table. The disks are electrically heated, current wires 22 having secured at one end thereof a plug 23 adapted to be received by a floor socket in the usual manner, passing up through the pedestal 5 and having secured at their opposite ends a swivel block 24 arranged in a suitable recess in the section 12. The block is held stationary within the recess by means of a post 28 which supports the latter, the post 100 being secured in any suitable manner to cross bars arranged within the pedestal 5. The block is centrally bored and receives the stem 29 of a multiple tap 25, the latter lying flush with the upper surface of the section 12. The stem 29 is provided with spaced superimposed annular flanges 30 forming electrical contacts co-operating with the contacts 31 carried by the free ends of the wires 22 to close the circuit. Leading from the multiple tap 25 through the various disks 21 are independent current wires 26,

the latter having secured to their inner ends push plugs 27 adapted to be removably secured in the suitable sockets in the multiple tap 25, the opposite ends thereof being connected in any suitable manner with the disks 21. The tap 25 is keyed to the section 12 of the table top as shown at 32, to rotate therewith, and by reason of the construction just described the section 12 10 may be rotated without twisting or otherwise interfering with the current wires 26. Each of the wires 26 is provided with a separate cut-off 33 so that the disks can be independently heated as the occasion may require. Manifestly certain foods can be initially heated or cooked upon the table, as well as being kept hot for a considerable length of time subsequent to being placed upon the disks.

20 It is believed that the nature and advantages of the invention will be thoroughly understood from the foregoing description without requiring a more extended explanation and therefore the same has been omitted. However, I desire to have it understood that the heating means may be employed with tables of ordinary construction as well as with tables of the type disclosed, and that furthermore I do not limit myself to the precise construction and arrangement of parts as shown, this being merely illustrative, and that various changes may be resorted to when desired as fall within the scope of the appended claims.

35 What I claim is:—

1. A table including a hollow pedestal, cross bars fixed thereto, a top supported by

said bars and comprising a stationary section and a revoluble center, electrically heated disks fixed on said center, current wires passing through said pedestal, a multiple tap, a swivel connection between said tap and wires, wires leading from said tap to the disks and connected therewith, and an independent cut-off for each of said disks.

40

2. A table comprising a top including a revoluble center, a plurality of electrically heated elements arranged upon said top, a hollow block arranged within a central recess in said top, contacts arranged within said block, a multiple tap arranged within said block and keyed to said center to rotate therewith, current wires connected with said block, and wires leading from said tap to said heating elements.

45

3. A table including a pedestal, cross bars fixed thereto, a rotatable top supported by said bars, electrically heated disks arranged on said top, a hollow block fitted within a central recess in the top, a flanged post extending within said recess for supporting said block, contacts arranged within said block, a multiple tap rotatably mounted in said block, current wires connected with said contacts, wires leading from said tap to said heating elements and detachably connected with the latter, and an independent cut-off for each of said elements.

50

In testimony whereof I affix my signature in presence of two witnesses.

WEBER J. FOX.
